FISHING SIGNAL DEVICE

Lawrence L. Muehl and Theodore Montgomery, both of
Box 113, Frankfort, S. Dak. 57440

Filed Feb. 8, 1973, Ser. No. 330,658

Term of patent 14 years

Int. Cl. D22—05

U.S. Cl. D22—23

FIG. 1 is a perspective view of a fishing signal device, showing our new design;

FIG. 2 is a side elevational view thereof;

FIG. 3 is a top plan view thereof;

FIG. 4 is a side elevational view showing the side opposite to that shown in FIG. 2;

FIG. 5 is a bottom plan view;

FIG. 6 is a front end elevational view; and

FIG. 7 is a rear end elevational view of a fishing signal device.

We claim:

The ornamental design for a fishing signal device, as shown.
